UNITED STATES PATENT OFFICE.

WILLIAM CONNER, OF PHILADELPHIA, PENNSYLVANIA.

HAT.

1,212,132.

Specification of Letters Patent.

Patented Jan. 9, 1917.

Application filed February 16, 1916. Serial No. 78,568.

To all whom it may concern:

Be it known that I, WILLIAM CONNER, citizen of the United States, and a resident of Philadelphia, county of Philadelphia, and State of Pennsylvania, have invented certain new and useful Improvements in Hats, of which the following is a specification, reference being had to the accompanying drawing.

10 A principal object of my invention is to provide means whereby a soft and resilient cushion shall be constantly presented for contact with the head of the wearer of the hat; to provide means whereby a hat may 15 be made substantially self-conforming, thus avoiding, except in extreme cases, the necessity of shaping or blocking the hat in order to adapt it to individual peculiarities 20 in the form or configuration of the head of the person by whom it is intended to be worn, and to provide cushioning means which shall be effective during the life of the hat and which will not become inoperative 25 through age or constant usage, so that the sweat band shall always present a soft and yielding surface to the head of the wearer when the hat is in use.

Further objects of my invention are to 30 provide cushioning means having the foregoing characteristics, which shall not add materially to the cost of manufacture of the hat; which shall not detract from the appearance of the finished hat, and which 35 may be readily embodied in any desired type or style of hat.

My invention further includes all of the other various novel objects and features of construction and arrangement hereinafter more definitely specified and described.

40 In the accompanying drawing the invention is shown as embodied in a Derby hat of ordinary form, although it will be understood that the invention is equally adapted for use in other types or styles of hats, Figure 1. being a central vertical, longitudinal section through the hat, showing a preferred embodiment of the invention, a portion of the sweat band of the hat being broken away and turned down for the sake 45 of clearness; Fig. 2. an enlarged, fragmentary, vertical, longitudinal central section the parts being shown in operative position, and Fig. 3, a similar view with 50 certain of the parts turned down to more readily illustrate the construction. Fig. 4. is an enlarged, fragmentary view similar to

Fig. 2. illustrating a slightly modified form of the invention.

Referring now to that form of the invention illustrated in Figs. 1-3 inclusive, the same is shown in a Derby hat of ordinary form having the usual body 1, brim 2, and sweat band 3. For the purpose of securing the sweat band within the hat, a strip of oiled silk or other material 4, which is preferably of relatively less thickness than as shown in the drawing, is folded over a suitable wire or cord 6 and secured adjacent the inner periphery of the hat body by suitable stitches 8 extending through the material 4 adjacent the wire and into the hat body in the usual manner, the free ends 9 of the material projecting upwardly for a short distance into the hat. The lower edge 12 of the sweat band is adapted to be secured to 75 the material 4 by suitable stitching 13 in such manner that the sweat band when in operative position will extend upwardly into the body of the hat as shown in Fig. 1. in the ordinary way. Instead, however, of 80 utilizing a sweat band having a length substantially equal to the circumferential length of the interior of the hat body 1 adjacent the wire 6, a sweat band of some- 85 what shorter length is employed, and during the operation of attaching it to the material 4 the sweat band is worked or stretched toward the front of the hat along the wire or cord 6, which is known in the art as "drumming" and results in causing 90 the sweat band in the finished hat to stand out from the interior of the hat, leaving a space 14 between the band and the hat body. In the preferred embodiment of my invention, I so proportion the length of the sweat 95 band to the length of the wire or cord 6, which in practice is substantially that of the interior circumferential length of the hat body adjacent its lower edge, that the band may be drummed for about one half of the 100 distance from the front of the hat to the rear thereof on either side of the median line. Hence in the finished hat the space 14 will extend for a substantially similar distance, while in the rear portion of the 105 hat the sweat band will lie closely adjacent the interior of the body as shown in Fig. 1.

Between the sweat band 3 and the body 1 of the hat and adjacent the front thereof, (which in the drawing is directed toward the right hand edge of the sheet,) and extending rearwardly on either side of the

median line, is positioned a suitable strip or band of resilient material 15 hereinafter referred to as the "pad" and which in the finished hat is designed to lie within the space 14 formed between the drummed portion of the sweat band and the interior of the hat body. While the pad may be formed of any desired material and in varying ways, I prefer to make the same of sheet rubber or the like, the sheet being folded over to form a loop and the free edges of the material being covered or bound with a relatively non-stretchable band or strip 16 of cloth or other suitable material secured thereto in any suitable and convenient manner, as by means of suitable stitches 18, extending through the cloth and through the pad. In practice, this strip 16 is of relatively less thickness than as shown in the drawing, where the proportions are exaggerated for the sake of clearness. Instead, however, of merely sewing or otherwise uniting the strip 16 to the pad when the latter is in normal condition and before securing it in the hat as hereinafter described, the strip is preferably sewed to the pad when the latter is under a considerable longitudinal strain or tension, whereby it is somewhat elongated. For example, when the pad has a normal length of say six inches, it is preferably stretched to a length of approximately eight inches before the strip is secured thereto. Of course, after this operation is accomplished and the tension upon the pad is released, the latter will resume its normal length, in consequence fulling or puckering up the strip 16, but when the latter is secured in the hat, as hereinafter described, the strip is stretched sufficiently to do away with this puckering or fulling.

While the strip and the resilient pad may be made of any desired length, in practice it is considered desirable to have them extend in the finished hat for about one-half of the distance from the front of the hat to the rear and on either side of the median line; that is, for about the same distance or a little less than the drumming preferably extends, although if desired, the sweat band can be drummed for the full length of the wire and the pad and its adjacent strip arranged to extend for the whole distance around the interior of the hat, or any desired fraction thereof.

The process of assembling a hat embodying the invention is substantially similar to that at present employed in hats of the usual type, and may consist in suitably securing the oiled silk or other material 4 which has been folded over the wire 6, to the interior of the hat, with the wire adjacent the edge thereof by stitching 8 in such manner that the free ends 9 of the material extend normally upward into the body

of the hat the sweat band being secured to the material 4 by stitches 13 in the ordinary manner, during which operation the sweat band is drummed or fulled preferably for about half the distance from the front to the back of the hat as has hitherto been described. It will be understood that this operation is usually accomplished with the sweat band turned down or away from the body of the hat, and that after the band has been secured in place, or if desired, before that operation has been completed, the pad 15 may be secured to the free upwardly projecting portions of the material 4 inclosing the wire 6, preferably by means of suitable stitches 20 extending through the strip 16, the pad inclosed by it, and the free ends of the material 4, the edges of the pad covered by the strip 16 extending upwardly within the hat and substantially parallel with the free ends 9 of the material 4. It will be understood that during this operation the strip 16 is extended to substantially its normal length so that after it is secured in place the rubber or other resilient material forming the body of the pad will be constantly subjected to a considerable longitudinal tension. The various parts having been assembled, the sweat band may be turned up into the hat to assume its normal operative position, which operation will serve to turn the pad over upon itself to assume the position shown in Figs. 1 and 2, in which it will rest between the sweat band and the body of the hat in space 14.

It will thus be seen that a soft resilient cushion is provided preferably in the front part of the hat and at that portion thereof which normally engages the forehead and temples of the wearer, and that this cushion will not mat down and become useless after the hat has been worn for some time owing to the resiliency of the pad and its constant tendency to force the sweat band away from the interior wall of the hat body, whereby the band is prevented from stretching and its spaced relation with the body of the hat adjacent the forehead and temples of the wearer continually preserved.

In Fig. 4, is shown a slightly modified form of the invention, in which the pad 25, is formed of a single sheet of rubber or other suitable material, instead of a folded sheet as in the form of the invention heretofore described, this sheet being united to the strip or binding 16 while under tension, and the whole secured to the material 4 inclosing wire 6 during the operation of assembling the hat in a manner similar to that heretofore described, the operation of the pad in the finished hat in this form of the invention being substantially similar to that of the pad 15 in the preferred form of the invention.

In order to clearly illustrate the details

of the invention, it has been necessary to materially exaggerate the proportions of certain of the elements shown in the drawing, as for example, the thickness of the material 4 and of the strip 16, but it is believed that the necessity for such exaggeration will be readily comprehended by those skilled in art, and that the relative proportions of these parts in the commercial embodiment of the invention will be clearly understood.

While I have herein illustrated and described certain embodiments of my invention with considerable particularity, I do not thereby intend or desire to limit myself specifically thereto, as it will be evident that various changes and modifications may be made in the details of construction and arrangement of the various parts of the invention and that the various elements comprising the finished hat may be assembled in any desired or convenient way other than that herein described, and that other suitable changes and modifications may be made without departing from the spirit and scope 25 of the invention as defined in the appended claims.

Having thus described my invention, I claim and desire to protect by Letters Patent of the United States:

1. In a hat, the combination with a hat body, of a sweat band, and tensioned resilient material disposed between said band and said body independent of said band and extending partially around the periphery thereof.

2. In a hat, the combination with a hat body, of a sweat band spaced from the interior of said body, and resilient material 40 under tension unconnected to said band and disposed in the space between said body and said band operative to maintain said band in its spaced relation with said body for a portion of its length.

3. In a hat, the combination with a hat body, of a sweat band spaced for a portion of its length from the interior of said hat body, and resilient material under longitudinal tension disposed in the space between 50 said body and said band and independent thereof operative to maintain said band in its spaced relation with said body.

4. In a hat, the combination with a hat body, of a sweat band spaced from the interior of said body for a portion of its 55 length and resting closely adjacent said hat

body for the balance of its length, and resilient means normally under longitudinal tension disposed between the hat body and that portion of the sweat band spaced therefrom and independent of said band operative to maintain said portion of said sweat band in spaced relation with said body.

5. A hat comprising a hat body, a sweat band, means to secure said sweat band in operative relation with said body, said sweat band being initially arranged in spaced relation with the interior of said body, and longitudinally tensioned resilient means secured to said first mentioned means and normally disposed between said sweat band and said body independent of said band and extending partially around the periphery thereof operative to maintain the initial spaced relation of said sweat band and said body when said hat is in use.

6. A hat comprising a hat body, a sweat band, means to secure said sweat band in operative relation with said body, said sweat band being initially arranged in spaced relation with the interior of said body for a portion of its length, and tensioned resilient means secured to said first mentioned means and normally disposed between and freely movable with respect to said sweat band and said body adjacent that portion of the sweat band which is spaced from said hat body, said resilient means being operative to maintain the initially spaced relation of said sweat band and said body when said hat is in use.

7. In a hat, the combination with a hat body, of a sweat band, means for securing said band to said body, and a piece of resilient material under longitudinal tension 95 and having an edge bound with relatively non-stretchable material secured within said hat body between said sweat band and said body.

8. In a hat, the combination with a hat body, of a sweat band, means for securing said band in said body, and a piece of tensioned folded resilient material doubled upon itself and having an edge bound with relatively non-stretchable material attached 105 to said band-securing means and disposed within said hat body between said band and said body.

In witness whereof I have hereunto set my hand this 15th day of February, A. D. 110 1916.

WILLIAM CONNER.
